United States Patent Office

Des. 190,730
Patented June 27, 1961

190,730

BUILDING BLOCK

William F. Mellin, 671 D St., San Bernardino, Calif.

Filed July 19, 1960, Ser. No. 61,432

Term of patent 14 years

(Cl. D18—2)

Fig. 1

Fig. 2

Fig. 3

FIG. 1 is a front perspective view of a building block embodying my new design;

FIG. 2 is a rear elevational view thereof; and
FIG. 3 is an end elevational view thereof.

I claim:

The ornamental design for a building block, as shown.
